CLAIM

I claim the ornamental design for an belt, as shown and described.

DESCRIPTION

FIG. 1 is a front isometric view of my new design;

FIG. 2 is a top plan view thereof;

FIG. 3 is a front elevation view thereof;

FIG. 4 is a right side elevation view thereof;

FIG. 5 is a rear elevation view thereof;

FIG. 6 is an enlarged isometric view thereof of the area encircled 6 in FIG. 1; and,

FIG. 7 is an enlarged front view thereof of the area encircled 7 in FIG. 5.

A design bottom plan view has been omitted, as it is a mirror image of the top plan view of FIG. 2.

The portions of the belt depicted in the figures in broken lines form no part of the claimed design.
